UNITED STATES PATENT OFFICE.

EBERHARD FABER, OF WEST NEW BRIGHTON, NEW YORK.

DESIGN FOR A RUBBER RING.

SPECIFICATION forming part of Design No. 20,696, dated April 28, 1891.

Application filed March 26, 1891. Serial No. 386,567. Term of patent 7 years.

To all whom it may concern:

Be it known that I, EBERHARD FABER, a citizen of the United States, residing at West New Brighton, in the county of Richmond and State of New York, have invented a Design for a Rubber Ring, of which the following is a full, clear, and exact description.

The leading feature of this design consists in the stripes of varying color running around the same diagonally.

In the drawings, Figure 1 is a side view, and Fig. 2 a section, of said ring.

The narrow stripes of contrasting color pass around the ring diagonally, as represented, and produce an acceptable artistic appearance.

I claim—

The design for a rubber ring herein shown and described.

Signed by me this 20th day of March, 1891. 20
EBERHARD FABER.

Witnesses:

L. W. FABER,
I. G. OSBORN.
